UNITED STATES PATENT OFFICE.

IRA D. SIEGFRIED, OF CLEVELAND, OHIO.

CALCULATING-MACHINE.

1,019,996.

Specification of Letters Patent.

Patented Mar. 12, 1912:

Application filed June 30, 1911. Serial No. 636,305.

To all whom it may concern:

Be it known that I, IRA D. SIEGFRIED, a citizen of the United States, residing at Cleveland, in the county of Cuyahoga and State of Ohio, have invented a certain new and useful Improvement in Calculating-Machines, of which the following is a full, clear, and exact description.

The object of this invention is to provide a simple, compact and easily operated calculating machine, on which results in addition, subtraction, multiplication and division, but more especially addition, may be readily and accurately registered or indicated to any desired amount.

The invention consists in a series of rotary dials inclosed in a casing and each having its own window or exposure opening in the case with a separate numeral exposing window; these dials being turned by the operator through the medium of a pencil point or other instrument to register the result of the operation in dollars and cents, or other units, to any amount, and being so connected and arranged as to respond to a manually operated resetting mechanism to rearrange all of the dials at zero for another operation, all as I will proceed now more particularly to explain and finally claim.

In the accompanying drawings illustrating the invention, in the several figures of which like parts are similarly designated, Figure 1 is a top plan view of a complete machine adapted to calculate into hundreds of thousands of dollars. Fig. 2 is a top plan view with the outer casing removed. Fig. 3 is a front elevation, casing omitted. Fig. 4 is a top plan view, on a larger scale, casing removed, showing several of the dials and their coacting advancing mediums. Fig. 5 is an end elevation, partly in section, casing off, but showing the device horizontal instead of canted, as it would naturally be and as shown in Fig. 10. Fig. 6 is an elevation of one of the counters, with the cam-operating plate in section. Fig. 7 is a plan view of the cam-operating plate, with the cam in position and a dial in dotted lines. Fig. 8 is a cross-section, on a larger scale, of the cam-operating plate, showing a part of the cam in elevation. Fig. 9 is a plan view of part of the main or dial plate. Fig. 10 is an end view on the same scale as Figs. 1 to 3, designed to show the canted or tilted position of use.

Without thereby limiting the invention to

the details shown, or to a machine of the specific construction and capacity or function herein explained, I will proceed to explain the construction shown in the drawings.

A base-plate 1, on which the parts are mounted, has a flange 2 on its front edge which serves to cant the machine so as to accommodate the user's eyes and as a guide on a ledger or other account book or device as the machine is moved thereon. Above this base-plate is a fixed main or dial plate 3, supported upon the base plate by posts 4 rising from the base plate and secured to both. Between the base-plate and the main-plate is a movable plate 5 which has fastened to it four, more or less, rods 6, which project up through holes in the dial plate and receive a bar 7.

Stepped in the base-plate 1, shown more particularly in Fig. 5, are two series of rotary shafts 8 and 9, which extend up through similar slots 10 and 11 in the front and rear of plate 5, to receive the dials and the dial-actuating mechanism, as presently described. The shafts 9 have longitudinal play in their step sockets so as to be vertically movable in order to reset the dials on shafts 8, as hereinafter explained.

The plate 5 is normally pressed toward the plate 3 by means of any number of coiled springs 12 supported by the posts 6 or any number of them, and so as to hold the plate 5 normally free of certain cams 13 and 14 on the shafts 8 and 9, respectively, during the operation of the dials in counting or calculating. The cams 13 and 14 are tubular in form and surround the shafts 8 and 9, excepting that at their lowest points the recess or groove 15 is made in each cam, and these cams are fixed to and turn with the shafts. The slots 10 in the movable plate 5 resemble key-hole slots, and their circular ends are provided with tongues 16 slightly depressed below the level of the plate, and having their underside chamfered off or beveled, as shown more particularly in Fig. 8, so that when said plate 5 is depressed by pressure upon the bar 7 against the tension of the springs 12, the tongues 16 will ride upon the cams and so rotate the shafts and restore the shafts to their normal position, which, as will presently appear, is with the dials at zero. Inasmuch as the plate 5 is attached to the bar 7 throughout its length, all of the cams that have been moved in the

operation of calculating will be restored to the zero position simultaneously. The tongues 16 are depressed so as to be arrested by the base-plate before it is possible for 5 them to escape from the cams.

The slots 17 in the plate 3 through which the shafts 8 and 9 extend, are plain straight slots,—see Fig. 9—ending in curves to conform substantially to the circumference of 10 the shafts.

Upon the shafts 8 are fixed collars 18, which are located on the underside of the plate 3, and above these collars are other collars 19 supported on the upper surface of 15 the plate 3. In other words, the shafts engage opposite sides of the plate 3, and I prefer to interpose between the plate and the collars 19 tension springs 20 which have an upward pressure. On the first, third, and 20 every alternate shaft 8 is a disk 21, having ten spurs or teeth 22 projecting radially from its periphery, and above these disks are dials 23 in which are holes or cavities 24 to receive a pencil point or other implement by which the dials and shafts and 25 connected parts are rotated. On the alternate shafts between the first, third, and succeeding shafts are disks 25 which are surrounded by the dials 26 supplied with holes 30 24 as before, and these dials 26 are provided with ten peripheral spurs or teeth 22. Of course, the disks 25 might be omitted and any suitable spacer placed between the fixed plate 3 and the dials 26, so as to raise said 35 dials to the proper elevation above the fixed plate 3. The point is that each alternate spurred or toothed element is arranged in a different plane, and this so as to permit an arrangement of operating mechanism where- 40 by the dials will be successively operated to proceed from cents to dimes and from dimes to dollars, etc., or to meet any other system of enumeration. On the dials 23 and 26 are arranged numerals from one to zero, corre- 45 sponding numerically to the spurred or toothed element on the several shafts 8.

The cover or casing 27 is of a size and shape to inclose the dials and their appurtenances, excepting that openings or windows 50 28 are made of a size to expose the rows of holes 24 in the several dials, and each of these windows or openings 28 is provided with a window or sight opening 29 in line with and to expose the numerals on the dials one at a time, and these thus exposed numerals give the results of the successive calculations made on the machine.

In order to connect the various dials in 60 working series, the shafts 9 are provided with disks 30 having peripheral spurs corresponding in number and location with the spurs on the spurred elements on the respective shafts 8; and these disks 30 are provided with pawls 31 having springs 32, said pawls projecting into the paths of movement 65

of the successive spurred elements on the dial shafts. That is to say, the pawl on the disk arranged between the dial shafts for dimes and cents would be on the upper surface of the disk so as to be in line with the teeth on 70 the periphery of the dimes dial, while the pawl on the next adjacent shaft would be on the lower side of the disk so as to be in line with the teeth on the toothed disk beneath the dial of the dollars dial, and so on alter- 75 nately.

The shafts 9 are normally lifted by pressure of the springs 33, and in order to equalize the pressure of these springs, the springs 34 are interposed between the plates 5 and 3 80 on the opposite side, that is to say, on the side with the dials. This equalization of the pressure of the springs prevents the resetting mechanism from being cramped or binding. As already indicated, the shafts 9 are provided with cams, and the holes 10 in the plate 5 are alike for the shafts 9 and the shafts 8.

It will be observed that the springs acting upwardly upon the disks of the several shafts 8 and 9 serve to keep the spurred elements on the shafts 8 and the pawls on the shafts 9 in line, and consequently motion is appropriately transmitted from the cents dial to the dimes dial and from that to the dollars dial, and so on.

When the end of a calculation is reached, and it is desired to reset the machine for a fresh operation, downward pressure is exerted upon the bar 7, the first result of which is to release the upward pressure of the springs against the shafts 9, followed by the dropping of the disks on these shafts to a common level on the fixed plate 3, resulting in taking their teeth out of engagement with the teeth of the disks on the shafts 8 and the pawls on the shafts 9 out of line with the spurred elements on shafts 8, and then, upon a further descent of the bar 7 and attached plate 5, the tongues 16 on these plates will become operative upon the cams on the shafts 8 and rotate these shafts so as to bring their dials uniformly back to zero. Meanwhile, the tongues 16 in the holes 10 opposite the cams 14 on the shafts 9 will rotate these shafts so as to present their pawls in the proper position to engage the dials in the next succeeding operation to advance the dials in proper order.

As shown in Fig. 1, the windows 28 may be and preferably are surrounded by numerals from 1 to 9, which are appropriately located relatively to the numerals on the counting elements and the holes 24 in said elements, to guide the operator in placing the operating pencil in the hole corresponding to the number to be used.

The casing is provided with a stop element 35 extending alongside each sight opening 29 to arrest the pencil or other operating

tool and the rotation of the counting element when the desired numeral is exposed, or, in other words, when the counting element has been rotated into proper relation.

5. It is to be understood that my machine may be, by slight change, converted into a counter for automatically registering the number of articles produced by a machine. To this end, the resetting mechanism might 10 be locked against unauthorized or fraudulent operation, and the frame around the initial dial opened to expose a tooth of that dial to be connected up with the press or other machine whose product or output is to 15 be counted.

I have thus described one embodiment of the principle of my invention, but wish to be understood as not limiting the invention to mere details, since these may be varied 20 within the scope of the claims.

What I claim is:—

1. A calculating machine, having a series of successively operating dials, rotary shafts upon which these dials are fixed, successively 25 operating dial-actuating means, rotary shafts upon which they are mounted, cams on all of the shafts, a cam-actuating plate in operative engagement with the several shafts, and means to move said plate lengthwise of 30 the shafts so as to cause its cam-actuating element to act upon the cams on the shafts to reset the several shafts and their appurtenances after said shafts have been turned in making the calculation.

35. 2. A calculating machine, having a series of successively operating dials with spurred or toothed elements located at different heights, rotary shafts and cams thereon, said dials adapted to be operated manually, a 40 complementary series of dial-actuating devices including spurred disks, and pawls thereon to engage the spurs or teeth of said operating dials, rotary cam shafts adapted to be moved longitudinally and on which the 45 dial-actuating devices are mounted, and means to thus move said shafts to throw the dial-actuating devices into and out of engagement with said operating dials.

3. A calculating machine, having a series 50 of successively operating dials provided with toothed elements, rotary shafts upon which the dials are fixed, a series of successively operating dial-actuating toothed disks carrying pawls, rotary shafts on which said 55 disks are fixed and having longitudinal movements to bring their disks into and out of engagement with the toothed elements of the dials, cams on all of said shafts, and a movable plate in which the several shafts 60 are arranged and having cam-actuating tongues.

4. A calculating machine, having a series 65 of successively operating dials provided with toothed elements, rotary shafts upon which the dials are fixed, a series of successively

operating dial-actuating toothed disks carrying pawls, rotary shafts on which said disks are fixed and having longitudinal movements to bring their disks into and out of engagement with the toothed elements of the dials, cams on all of said shafts, a movable plate in which the several shafts are arranged and having cam-actuating tongues, and springs normally holding said plate out of engagement with the cams. 70

5. A calculating machine, having a series of successively operating dials provided with toothed elements, rotary shafts upon which the dials are fixed, a series of successively operating dial-actuating toothed disks carrying pawls, rotary shafts on which said disks are fixed and having longitudinal movements to bring their disks into and out of engagement with the toothed elements of the dials, cams on all of said shafts, a movable plate in which the several shafts are arranged and having cam-actuating tongues, springs normally holding said plate out of engagement with the cams, 75 and a bar secured to said plate by which pressure may be applied to the plate to first clear the dials from their actuating devices, and then engage the cams and reset the shafts, after which the springs are free to act to release the shafts for a fresh calculation. 80

6. A calculating machine, having a series of successively operating dials provided with toothed elements, rotary shafts upon which the dials are fixed, a series of successively operating dial-actuating toothed disks carrying pawls, rotary shafts on which said disks are fixed and having longitudinal movements to bring their disks into and out of engagement with the toothed elements of the dials, cams on all of said shafts, and a movable plate in which the several shafts are arranged and having cam-actuating tongues, said tongues being beveled and depressed. 90

7. A calculating machine, having a series of successively operated dials provided with toothed elements, a fixed dial plate in which said dials are arranged, springs interposed between the dials and dial-plate, rotary shafts upon which the dials are fixed, a 100 series of successively operating dial-actuating toothed disks carrying pawls, rotary shafts on which said disks are fixed and having longitudinal movements to bring their disks into and out of engagement with the toothed elements of the dials, cams on all 105 of said shafts, and a movable plate in which the several shafts are arranged and having cam-actuating tongues. 110

8. A calculating machine, having a series 115 of successively operated dials provided with toothed elements, a fixed dial plate in which said dials are arranged, rotary shafts upon which the dials are fixed, a series of successively operating dial-actuating toothed disks 120

125

130

carrying pawls, rotary shafts on which said disks are fixed and having longitudinal movements to bring their disks into and out of engagement with the toothed elements of the dials, cams on all of said shafts, and a movable plate in which the several shafts are arranged and having cam-actuating tongues, and springs interposed between the dial

plate and movable plate and in engagement with the several shafts.

10

In testimony whereof I have hereunto set my hand this 24th day of June A. D. 1911.

IRA D. SIEGFRIED.
